DESIGN FOR A COMBINATION PERFUME AND LIPSTICK HOLDER

John Rubel, New York, N. Y.

Application December 11, 1944, Serial No. 116,851

Term of patent 7 years

(Cl. D86—10)

To all whom it may concern:

Be it known that I, John Rubel, a citizen of the Republic of France who has declared his intentions of becoming a citizen of the United States, residing in New York city, in the county of New York and State of New York, have invented a new, original, and ornamental Design for a Combination Perfume and Lipstick Holder, of which the following is a specification, reference being had to the accompanying drawing, forming part thereof.

Fig. 1 is a front view of a combination perfume and lipstick holder showing my new design;

Fig. 2 is an end view of Fig. 1;

Fig. 3 is a side view of the lipstick holding portion from the holder shown in Figs. 1 and 2;

Fig. 4 is a side view of the perfume cap and applicator removed from the other end of the holder shown in Figs. 1 and 2;

Fig. 5 is a view of the combination holder in Fig. 1 with the button and chain removed for convenience of illustration.

I claim:

The ornamental design for a combination perfume and lipstick holder, substantially as shown.

JOHN RUBEL.
